UNITED STATES PATENT OFFICE.

GEORGE B. WILLIAMS, OF GARY, INDIANA.

DESIGN FOR AUTOMOBILE SIGNAL CASING.

Application filed March 9, 1923. Serial No. 5,423. Term of patent 7 years.

To all whom it may concern:

Be it known that I, GEORGE B. WILLIAMS, a citizen of the United States of America, residing at Gary, in the county of Lake and State of Indiana, have invented a new, original, and ornamental Design for Automobile Signal Casing, of which the following is a specification, reference being had to the

accompanying drawings, forming a part hereof.

The figure is a perspective view showing my automobile signal casing.

I claim:

The ornamental design for automobile signal casing as shown.

GEORGE B. WILLIAMS.
